Atty.

UNITED STATES PATENT OFFICE.

JOSEPH ADAMS, OF ROXBURY, MASSACHUSETTS, ASSIGNOR TO ADAMS-WHITE BRUSH COMPANY, OF BOSTON, MASSACHUSETTS, A CORPORATION OF MASSACHUSETTS.

ROTARY BRUSH.

Application filed September 27, 1924. Serial No. 740,174.

To all whom it may concern:

Be it known that I, JOSEPH ADAMS, a citizen of the United States of America, and a resident of Roxbury, in the county of 5 Suffolk and State of Massachusetts, have invented certain new and useful Improvements in Rotary Brushes, of which the following is a specification.

This invention relates to rotary brushes 10 and particularly to brushes of this character made up of a plurality of sections mounted upon a tubular member, the ends of which are secured to a revolute shaft.

The present invention consists in novel 15 means for assembling the elements of each section, novel means for preventing one section rotating independently of the other sections, novel means for stiffening the central portion of the tubular member on which 20 the sections are mounted, and novel means whereby the supporting shaft with the brush thereon may be readily removed from the bearings therefor.

The invention further consists in certain 25 novel features of construction and arrangement of parts which will be understood readily by reference to the description of the drawings and to the claims to be hereinafter given.

For the purpose of illustrating the invention, one preferred form thereof is illustrated in the drawings, this form having been found to give satisfactory and reliable results although it is to be understood 30 that the various instrumentalities of which the invention consists can be variously arranged and organized and the invention is not limited to the precise arrangement and organization of these instrumentalities as 35 herein shown and described except as required by the scope of the appended claims.

Of the drawings—

Figure 1 represents a longitudinal section 40 of a brush embodying the principles of the present invention, on line 1, 1 on Fig. 2.

Figure 2 represents a transverse section of the same, on the line 2, 2, on Fig. 1.

Figure 3 represents an end elevation of 50 the same, and

Figure 4 represents an edge view of one of the bristle clamping disks.

Similar characters indicate like parts throughout the several figures of the drawings.

In the drawings, 10 is a revolute shaft having mounted thereon the split disks 11 having split hubs 12.

Surrounding each split hub 12 is a collar 13 through which extends a set screw 60 14, this screw extending through a hub 12 and impinging upon the shaft 10 so that said disks 11 will rotate with said shaft.

The disks 11 have cylindrical portions which fit within annular flanges 15 projecting outwardly from the heads 16 which are secured to said disks 11 by means of screws 17. These heads 16 are threaded to the opposite ends of a tube 18 surrounding the shaft 10 and spaced therefrom.

Between the heads 16 and surrounding the tube 18 are a plurality of brush sections 19, one complete section being shown in the center of Fig. 1 of the drawings.

These brush sections 19 are composed of 75 a plurality of metal rings 20 the opposite faces of which are provided with a plurality of radial depressions 21, the depressions on one face being intermediate the depressions on the opposite face.

Each ring 20 has on each face thereof a thin layer of lead 22 forming a lining for the depressions 21.

When the rings 20 are assembled the depressions on adjacent faces are in register 85 and form cylindrical lead-lined holes in which are disposed clusters of bristles 23, the inner ends of said bristles being forced into the lead lining of the holes when the rings 20 are clamped together.

Each brush section 19 composed of a plurality of rings 20 when clamped together has positioned therein one or more tubular members 24 extending from end to end thereof with the outer ends of said tubular members 24 upset to retain each sectional unit intact.

When several of these sections or units 95 19 are mounted upon the tube 18 the tubular members 24 are brought into alignment 100

and rods 25 are inserted through the tubular members of the several units 19, these rods 25 effectually preventing one section or unit from rotating about the tube 18 independently of the other sections.

In fact the rods 25 form locks which compel the various sections to rotate together.

The heads 16 have screws 26 extending therethrough into the end units or sections 19 thereby insuring the rotation of the brush sections with the heads 16, and therefore with the shaft 10, said heads being locked to the disks 11 by means of the screws 17 and said disks being secured to the shaft 10 by means of the screws 14.

It is obvious, therefore, that all the brush sections 19 must rotate with said shaft 10 when rotary motion is imparted thereto in any machine in which it may be installed.

20 The tube 18 is usually of considerable length and requires some central support to prevent it from vibrating during its rotation and this support must be of such a character that it may be displaced when it is desired to remove the tube 18 from the shaft 10 in order to substitute new brush sections 19 for those which have become unserviceable.

30 In order to accomplish this object a split cylinder 27 is inserted into the center of the tube 18, said cylinder having sufficient length to stiffen the tube and prevent the vibration thereof.

35 When the cylinder 27 is contracted it can be inserted readily in the tube 18 but when it is expanded by the insertion of the tapered plug 28 into its tapered bore its periphery will be forced into rigid contact with the inner wall of the tube 18, so that it cannot 40 be displaced accidentally.

45 Any desired number of units 19 may be mounted upon the tube 18 and any number of rings 20 may be installed in each unit 19 so that the completed brush will be of such a length as to adapt it for any particular work for which it may be designed to perform.

With a filler such as the split cylinder 27 installed within the tube 18 intermediate its 50 ends, the tube is retained in perfect alignment during its rotation and all vibration of the brush is entirely eliminated.

55 By making the depressions 21 on one face of the rings 20 intermediate the depressions on the opposite face, the clusters of bristles 23 will be staggered with some of the bristles in each row overlapping the bristles in the adjacent rows.

60 When the bristles 23 become worn and it is desired to replace them, the upper part of each split disk 11 has the screws 17 removed therefrom so that said part may be removed, the collar 13 having first been removed from the hub 12.

65 When this has been done, the shaft 10 may

then be lifted out of the bearings in the lower part of the disks 11 and hubs 12.

The tapered plug 28 secured to the shaft 10 by a screw 29 is then removed from the cylinder 27 secured to the tube 18 by screw 30, when the shaft 10 is drawn out of the tube 18.

The tube 18 with the brush sections 19 thereon may then be sent to the brush assembling room, at which point the screws 26 75 may be removed from the heads 16 and one of heads removed from the tube 18.

The brush units 19 may then be slipped off of the tube 18 and replaced by new units 19, the head 16 screwed onto the tube 18 and 80 the screws 26 inserted through said heads into the end sections 19.

The tube 18, with the brush sections 19 mounted thereon and clamped together by the heads 16, is then returned to the machine and reassembled upon the shaft 10 in 85 the manner previously described.

This makes a very simple but effective means for constructing long rotary brushes 90 to be used in many classes of machines.

The operation and many advantages of the invention will be apparent without further description.

Having thus described my invention, I 95 claim:

1. The combination of a tube; annular heads secured to the opposite ends thereof; brush sections surrounding said tube between said heads; a tubular member extending through each brush section; and a 100 rod extending through the tubular members of all of said brush sections.

2. The combination of a tube; annular heads secured to the opposite ends thereof; brush sections surrounding said tube between said heads, each section being composed of a plurality of disks having radial depressions in the face thereof; and a shaft 105 secured to said heads and centrally disposed within said tube and separated from the inner wall thereof.

3. The combination of a tube; annular heads secured to the opposite ends thereof; a plurality of unitary brush sections surrounding said tube between said heads; means preventing independent movement of said brush sections; and screws extending through said heads into the outer brush sections.

4. The combination of a tube; annular heads secured to the opposite ends thereof; brush sections surrounding said tube between said heads and revolvable therewith; and a two-part filling member within and intermediate the ends of said tube, the two 115 parts of which are adjustable endwise relatively to each other.

5. The combination of a tube; annular heads secured to the opposite ends thereof; brush sections surrounding said tube be- 120

tween said heads and revoluble therewith; a split cylinder fitting the central portion of said tube and having a tapered bore; and a tapered plug within said cylinder.

5 6. The combination of a tube; annular heads secured to the opposite ends thereof; brush sections surrounding said tube between said heads and revoluble therewith; a split cylinder fitting the central portion of 10 said tube; and means for expanding said cylinder.

7. The combination of a tube; annular heads secured to the opposite ends thereof

provided with outwardly extending annular flanges; brush sections surrounding said tube 15 between said heads and revoluble therewith; a revoluble shaft; a divided disk fitting within said flange and having a cylindrical hub; a collar surrounding said split hub; and a screw extending through said collar 20 and hub and impinging upon said shaft.

Signed by me at 746 Old South Bldg., Boston, Mass., this 25th day of September, 1924.

JOSEPH ADAMS.
